J. HURWITZ.

SHIRT.

APPLICATION FILED MAY 12, 1919.

1,327,476.

Patented Jan. 6, 1920.

UNITED STATES PATENT OFFICE.

JOSEPH HURWITZ, OF NEW YORK, N. Y.

SHIRT.

1,327,476.

Specification of Letters Patent.

Patented Jan. 6, 1920.

Application filed May 12, 1919. Serial No. 296,408.

To all whom it may concern:

Be it known that I, JOSEPH HURWITZ, a citizen of the United States, and a resident of the city of New York, borough of Manhattan, in the county and State of New York, have invented new and useful Improvements in Shirts, of which the following is a full, clear, and exact description.

The object of the invention is to provide certain new and useful improvements in shirts of the negligée type whereby the worn out or torn portions can be conveniently removed, at the same time, however, displaying unused duplicate portions thus permitting the owner to practically use the shirt twice the length of time of an ordinary shirt of the same type. More specifically, one object is to permit of removing torn or worn out bosom portions without requiring the attachment of new portions and without altering the appearance of the shirt.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a front perspective view of the shirt as applied and with portions broken out and a corner of one of the bosom panels shown partly detached and folded back;

Fig. 2 is an enlarged inverted sectional plan view of the shirt on the line 2—2 of Fig. 1;

Fig. 3 is a cross section of another portion 40 of the shirt on the line 3—3 of Fig. 1;

Fig. 4 is an enlarged inverted sectional plan view of another portion of the shirt on the line 4—4 of Fig. 1;

Fig. 5 is an enlarged cross section of one 45 of the cuffs, the section being on the line 5—5 of Fig. 8;

Fig. 6 is an enlarged cross section of a portion of the shirt on the line 6—6 of Fig. 1;

Fig. 7 is a face view of a portion of the shirt made of striped material, one corner 50 of the outer bosom portion being shown detached and folded back; and

Fig. 8 is a face view of one of the cuffs 55 in extended position and with one corner of one of the layers detached and folded back.

The body 10 of the shirt is provided at the median line of the front with multi-ply or reinforced front flaps 11 and 12 adapted to overlap and to be fastened together in the usual manner by buttons and button-holes or other fastening devices 13. The upper ends of the flaps 11 and 12 are joined to the ends of the neckband 15 which like 60 the yoke 16 and the sleeves 17 are of usual construction so that further description of the same is not deemed necessary. Each of the bosom panels 20 and 21 of the shirt body 10 is provided with marginal hemstitchings 70 22, 23, 24 and 25, of which the hemstitching 22 is adjacent the corresponding flap 11 or 12. The hemstitchings 23 are adjacent folds 25 and 26 formed in the body 10 and extending from the front edge of the yoke 75 16 downward to approximately the waist portion of the skirt body, as plainly indicated in Fig. 1, it being understood that the folds 25 and 26 are approximately parallel 80 with the flaps 11 and 12. The upper marginal stitchings 24 are adjacent the front edge of the yoke 16 and the front portion of the neckband 15, and the lower marginal stitchings 25 are approximately at the waist line of the body. The flap 11 when in closed 85 position overlies the hemstitchings 22 of the panel 21 and the flap 11 has its right-hand side extended to normally overlap the marginal stitching 22 of the panel 20 and the folds 25 and 26 normally overlie the marginal stitchings 23 of the outer sides of the two bosom panels 20 and 21 and hence the marginal stitchings 22 and 23 are normally not visible.

The outer bosom panels 20 and 21 overlie 95 duplicate inner bosom panels 30 and 31 of the same material as the bosom panels 20 and 21, and of which the bosom panel 30 is fastened at the right-hand side by stitches 32 to the body 10 at the fold 25 and beyond the hemstitching 23, while the left-hand side of this duplicate inner bosom panel 30 is fastened by stitches 33 to the flap 11 (see Fig. 4) at a point beyond the hemstitching 22. The upper end of the inner bosom panel 30 is attached by stitches 34 and 35 to the yoke 16 and the collar band 15 at a point 100 beyond the hemstitching 24 and the lower end of the inner bosom panel 30 is connected by stitches 36 with the body 10 at a point 105 below the hemstitching 25, as plainly indicated in Fig. 1. The other inner bosom panel 31 is similarly connected by stitches 37 to the body 10 at the fold 26 beyond the 110

hemstitching 23, as plainly indicated in Figs. 1 and 2. The right-hand side of the inner bosom panel 31 is connected by stitches 38 and 39 to the flap 12 (see Fig.

- 5 4) and the upper end of the bosom panel 31 is connected to the yoke 16 and the corresponding end of the collar band 15 by stitches (not shown) but similar to the stitches 34 and 35, while the lower end of 10 the bosom panel 31 is connected by stitches 40 to the body 10 below the hemstitching 25, as plainly indicated in Fig. 6.

By the arrangement described, the bosom panels 20 and 21, in case they are worn out 15 or torn, can be cut out by cutting along the hemstitchings 22, 23, 24 and 25, thus allowing complete removal of these panels and thereby uncovering the inner panels 30 and 31 which now assume the functions of the 20 panels 20 and 21. It will be noticed that as the flap 11 normally overlies the stitchings 22, and the folds 25 and 26 overlie the hemstitchings 23, it is evident that the picots left on cutting the hemstitchings 22 and 23 25 are not visible and hence the shirt front has practically the same appearance as it had prior to cutting out the panels 20 and 21.

In case the body 10 is made of figured goods, as indicated in Fig. 7, then the figures of the panels 20, 30 and 21, 31 are 30 in register, and hence when the outer panels 20 and 21 are removed, as above explained, then the figures of the under panels 30 and 31 are in proper alinement with the remaining portions of the body.

It is understood that in practice the bosom of a shirt is usually ruptured at the upper portion by the ends of the collar and when this rupture takes place the shirt is practically rendered useless and, as a rule, is thrown away. With the improved shirt 40 having removable outer panels 20 and 21 the life of the shirt is practically doubled as the under panels 30 and 31 perform the same 45 functions as the panels 20 and 21 after the latter are removed.

Each of the cuffs 50 at the end of the corresponding sleeve 17 is provided with an outer detachable panel 51 normally overlying a panel 52, and this outer panel 51 is provided with marginal hemstitchings 53 which can be cut by the use of scissors or other tool whenever the panel 51 becomes worn out thus bringing into use another 55 panel 52. The panels 51 and 52 are connected with an inside panel 54 and the several panels are fastened together beyond the hemstitchings 53 by stitches 55 and 60 stitches 56 are used for fastening the inner ends of the panels to the sleeve 17, as plainly indicated in Fig. 5. A lining may be introduced between the panels 53 and 54 to stiffen the cuff in case it is desired to do so.

No overlying folds are necessary for the 65 upper and lower marginal hemstitches of

each outer panel 20 and 21 as these hemstitched portions are usually covered by vests and outer garments such as coats and trousers.

It is understood that although only one removable panel 20 or 21 is shown at each bosom part, it is evident that two or more such panels having hemstitched margins may be used in superimposed relation to allow of removing one panel after another as they become torn or worn out until the under panels 30 and 31 are reached. The same arrangement applies to the cuffs.

Having thus described my invention, I claim as new and desire to secure by Letters Patent:—

1. In a shirt, a divided front to provide two bosom parts, each having a plurality of superimposed panels and hemstitches along the margins of the outermost panel of each bosom part and adapted to be cut to detach the outermost panel of each bosom part from the shirt and to leave the under panel intact to perform the function of the detached panel.

2. In a shirt, a body provided with a neckband and with a divided front to provide two bosom parts having overlapping flaps for closing the front, each bosom part having a plurality of superimposed panels and hemstitches along the margins of the outermost panel adjacent the corresponding flap, the top, the waist line and sides of the said body, the said hemstitches being adapted to be cut to allow removal of the outermost bosom panels leaving the under bosom panels intact to perform the functions of the removed panels, the said flaps overlying the hemstitches along the margins connecting the panels with the flaps.

3. In a shirt, a body having a divided front providing two outer bosom panels each having hemstitched margins, vertical folds on the body and overlying the sides of each bosom panel and the corresponding hemstitched side margins, and inner bosom panels underlying the said outer bosom panels and attached to the body at the said hemstitched margins.

4. In a shirt, a body having a divided front providing two outer bosom panels each having hemstitched margins, a neckband, a yoke, flaps adapted to overlie to close the front of the shirt, side flaps extending approximately parallel to the front flaps and 115 extending from the said yoke, the said front and side flaps overlying the hemstitched side margins of the said outer panels, the hemstitched margin at the upper end of the outer panels being adjacent the said neckband and yoke, and inner bosom panels underlying the said outer panels and being attached to the body at the hemstitched margins of the outer panels.

JOSEPH HURWITZ.
